DESIGN FOR A STOCKING OR SIMILAR ARTICLE

Charles S. Greenwald, New York, N. Y.

Application January 8, 1941, Serial No. 97,851

Term of patent 3½ years

To all whom it may concern:

Be it known that I, Charles S. Greenwald, a citizen of the United States of America, residing in New York city, county of New York, and State of New York, have invented a new, original, and ornamental Design for a Stocking or Similar Article, of which the following is a specification, reference being had to the accompanying drawing, forming part thereof.

The figure on the drawing is a perspective view of a stocking or similar article showing my new design.

The unfinished parts of the stocking are to be finished in a manner as shown by the areas illustrated in full lines.

I claim:

The ornamental design for a stocking or similar article, as shown and described.

CHARLES S. GREENWALD.
